Primary Examiner — Catherine Tuttle(74) *Attorney, Agent, or Firm* — Gottlieb, Rackman & Reisman, P.C.(57) **CLAIM**

The ornamental design for a perfume bottle, as shown and described.

DESCRIPTION

FIG. 1 is a perspective view of the perfume bottle, showing my new design;

FIG. 2 is a top plan view thereof;

FIG. 3 is a front elevational view thereof;

FIG. 4 is a right side elevational view thereof, the left side elevational view being a mirror image;

FIG. 5 is a rear elevational view thereof;

FIG. 6 is a bottom plan view thereof;

FIG. 7 is a perspective view of the perfume bottle in a standing position with a decorative tassel surrounding the base of a cap of the bottle; and,

FIG. 8 is an exploded perspective view thereof.

The broken lines shown in FIGS. 1, 3-5 and 7-8 are for illustrative purposes only and form no part of the claimed design.
